[57] CLAIM

The ornamental design for a combined shower head and soap dispenser for animals, as shown.

DESCRIPTION

FIG. 1 is an isometric view of a combined shower head and soap dispenser for animals showing my new design;

FIG. 2 is a top plan view thereof;

FIG. 3 is a rear elevational view thereof;

FIG. 4 is an elevational view taken from one side thereof;

FIG. 5 is an elevational view taken from the side opposite that shown in FIG. 4;

FIG. 6 is a front elevational view thereof; and

FIG. 7 is an enlarged fragmentary elevational view taken on line 7—7 of FIG. 5.
